(57) **CLAIM**

I claim the ornamental design for a watchband bottle opener apparatus, as shown and described.

DESCRIPTION

FIG. 1 is a front perspective view of a watchband bottle opener apparatus;

FIG. 2 is a top elevation view thereof;

FIG. 3 is a side perspective view thereof;

FIG. 4 is an end plan view thereof;

FIG. 5 is a side plan view thereof;

FIG. 6 is a bottom front perspective view thereof;

FIG. 7 is a bottom plan view thereof; and,

FIG. 8 is a bottom rear perspective view thereof.

Broken lines illustrate environmental features and form no part of the claimed design.
